US0D1061145S

(12) **United States Design Patent** (10) **Patent No.:** **US D1,061,145 S**
(45) **Date of Patent:** **** Feb. 11, 2025**

(54) **APPLIANCE RECESSED WINDOW BEZEL**

(71) Applicant: **WHIRLPOOL CORPORATION**,
Benton Harbor, MI (US)

(72) Inventors: **Kaitlyn M. Benoit**, St. Joseph, MI
(US); **Michael A. Kahwaji**, St. Joseph,
MI (US); **Brandon T. Mock**, St.
Joseph, MI (US); **Jason W. Tippets**,
Stevensville, MI (US)

(73) Assignee: **WHIRLPOOL CORPORATION**,
Benton Harbor, MI (US)

(**) Term: **15 Years**

(21) Appl. No.: **29/842,084**

(22) Filed: **Jun. 10, 2022**

Related U.S. Application Data

(60) Division of application No. 29/694,845, filed on Jun.
13, 2019, now Pat. No. Des. 957,190, which is a
continuation of application No. 29/605,378, filed on
May 25, 2017, now Pat. No. Des. 855,395, which is
a division of application No. 29/483,020, filed on Feb.
25, 2014, now Pat. No. Des. 788,523.

(57) **CLAIM**

The ornamental design for an appliance recessed window bezel as shown and described.

DESCRIPTION

FIG. 1 is a front perspective view of an appliance recessed window bezel of the present disclosure;

FIG. 2 is a front elevational view of the appliance recessed window bezel of FIG. 1;

FIG. 3 is a front perspective view of another embodiment of an appliance recessed window bezel of the present disclosure;

FIG. 4 is a front elevational view of the appliance recessed window bezel of FIG. 3;

FIG. 5 is a front perspective view of another embodiment of an appliance recessed window bezel of the present disclosure; and,

FIG. 6 is a front elevational view of the appliance recessed window bezel of FIG. 5.

The portions of the article shown in broken line form no part of the claimed design.

1 Claim, 6 Drawing Sheets
